(57) **CLAIM**

The ornamental design for a baby garment with double zipper and removable hood, as shown and described.

DESCRIPTION

FIG. 1 shows a front perspective view of a baby garment with double zipper and removable hood;

FIG. 2 shows a front plan view of the baby garment with double zipper and removable hood of FIG. 1;

FIG. 3 shows a rear plan view of the baby garment with double zipper and removable hood of FIG. 1;

FIG. 4 shows a right plan view of the baby garment with double zipper and removable hood of FIG. 1;

FIG. 5 shows a left plan view of the baby garment with double zipper and removable hood of FIG. 1;

FIG. 6 shows a top plan view of the baby garment with double zipper and removable hood of FIG. 1;

FIG. 7 shows a bottom plan view of the baby garment with double zipper and removable hood of FIG. 1;

FIG. 8 shows a rear plan view of the baby garment with double zipper and removable hood of FIG. 1 with the fold-over hand portions flipped over the baby's hands;

FIG. 9 shows a right plan view of the baby garment with double zipper and removable hood of FIG. 1 with the fold-over feet portions flipped over the baby's feet;

FIG. 10 shows a perspective view of the baby garment with double zipper and removable hood of FIG. 1 with the hood off of the baby's head and top zipper cover open to show the top zipper; and,

FIG. 11 shows a rear view of the baby garment with double zipper and removable hood of FIG. 1 showing fasteners of the collar and a front view the hood removed from the garment to show fasteners on the hood.

The broken lines shown in the drawings form no part of the claimed design.

1 Claim, 11 Drawing Sheets
